UNITED STATES PATENT OFFICE

97,587

DESIGN FOR A VEHICLE ORNAMENT OR SIMILAR ARTICLE

Howard F. Yaeger, Detroit, Mich., assignor to
Packard Motor Car Company, Detroit, Mich.,
a corporation of Michigan

Application January 30, 1935, Serial No. 55,154

Term of patent 3½ years

To all whom it may concern:

Be it known that I, Howard F. Yaeger, a citizen of the United States, residing at Detroit, county of Wayne, State of Michigan, have invented a new, original, and ornamental Design for a Vehicle Ornament or Similar Article, of which the following is a specification, reference being had to the accompanying drawing, forming a part thereof, and in which:

Fig. 1 is a plan view of an ornament incorporating my new design;

Fig. 2 is a side elevational view thereof;

Fig. 3 is a front elevational view thereof.

The present design comprises as the principal and dominating features thereof an elongated body having a symmetrical vertical section, the

rear two-thirds of said body being uniformly symmetrical, and said body being formed with a pair of identical side fins terminating in a point to form a substantially spear-head configuration, and one end of the body having its lower portion formed by an enlargement which constitutes the supporting part of the body and which enlargement is swelled out so that its profile near the front end forms a single convex sweeping curve that extends to the base of the design.

I claim:

The ornamental design for a vehicle ornament or similar article, as shown and described.

In testimony whereof I affix my signature.

HOWARD F. YAEGER.
